COVER FOR SHOWER HEAD

Ralph La Rue Du Bois, 4242 E. 111th St., Tulsa, Okla. 74136

Filed July 23, 1973, Ser. No. 382,084

Term of patent 14 years

Int. Cl. D23—01

U.S. Cl. D23—36

FIG. 1.

FIG. 2.

FIG. 3.

FIG. 1 is an elevational view taken from one side of a shower head cover showing my new design, the opposite side being a mirror image of the side shown.

FIG. 2 is a top plan view thereof; and

FIG. 3 is a bottom plan view thereof.

I claim:

The ornamental design for a cover for shower head, substantially as shown and described.
